M. S. HOTCHKISS

CONCRETE WALL FORM

Filed Nov. 1, 1921

*M. J. Inventor
Hotchkiss
By Howard D. Denison
Attorney.*

UNITED STATES PATENT OFFICE.

MARK S. HOTCHKISS, OF JOHNSON CITY, NEW YORK.

CONCRETE-WALL FORM.

Application filed November 1, 1921. Serial No. 511,985.

To all whom it may concern:

Be it known that I, MARK S. HOTCHKISS, of Johnson City, in the county of Broome, in the State of New York, have invented 5 new and useful Improvements in Concrete-Wall Forms, of which the following, taken in connection with the accompanying drawings, is a full, clear, and exact description.

This invention relates to concrete wall 10 forms of the sectional or panel type capable of being progressively erected tier by tier or panel by panel from the bottom upward as the construction work of the wall progresses and also of being easily and quickly 15 removed after the concrete has hardened or set sufficiently to be self-sustaining.

The main object is to provide simple and efficient means whereby the panel forms and their supports may be expeditiously 20 erected as the work progresses, and removed as the work is finished for reuse in other places.

Another object is to provide means for 25 bracing the panel-supporting-studs as they are erected to hold them in parallel or proper relation to each other for the reception of the panels.

A further object is to provide the upright panel-supporting-studs with means for 30 attachment to suitable staging or scaffolding to facilitate the continued erection of superposed panels.

Other objects and uses relating to specific 35 parts of the form will be brought out in the following description:

In the drawings:

Fig. 1 is a perspective view of portions of the forms as used for constructing concrete 40 walls around the corner of the building.

Fig. 2 is an enlarged vertical sectional view of a portion of one of the upright studs and adjacent end of one of the scaffolding supports showing the interlocking connection between those parts.

Fig. 3 is a horizontal sectional view 45 through one of the studs and adjacent ends of adjacent panels as shown in Figure 2.

Fig. 4 is an outer face view of a portion 50 of one side of one of the upright columns and adjacent portion of one of the panels interlocked therewith.

Fig. 5 is an enlarged vertical sectional view of a portion of one of the panels and adjacent edge of one of the transverse parti-

tions showing the interlocking connections 55 between those parts.

Fig. 6 is a detail sectional view taken in the plane of line 6—6, Fig. 5.

Fig. 7 is a detail sectional view of the upper end of one of the braces and adjacent 60 portion of one of the upright studs showing the interlocking connection between one of those parts.

Fig. 8 is an inner face view of one of the 65 studs showing the same interlocking connection.

Figs. 9 and 10 are, respectively, side elevations of the lower end of the brace showing the foot by which it is secured to the ground or other suitable support. 70

Fig. 11 is an enlarged detail sectional view taken in the plane of line 11—11, Fig. 8.

In the construction of concrete walls with the forms shown, a footing course —A— 75 preferably of concrete is first laid to the desired depth and width for supporting the wall and after the footing course has become sufficiently hardened or set, a series 80 of sheet metal studs —1— are supported thereon in upright parallel positions and preferably in uniformly spaced relation longitudinally at the inner and outer sides of the proposed wall directly opposite each other, and are held against outward displacement by braces —2— or receiving between them sheet metal panels —3—, said 85 columns being held against inward displacement by braces —4— of substantially the same length as the width of the wall, the 90 columns being drawn tightly against the ends of the braces —4— by twisted wires —5— or equivalent tightening means.

One or more sheet metal partitions —6— 95 may be placed in operative position between the inner and outer panels to form headers for window and door reveals and any other openings which it may be desired to leave in the walls.

The studs are preferably made of heavy 100 sheet metal rolled or otherwise pressed in the form of channel bars having their channels as —7— facing inwardly and their inner edges bent outwardly to form laterally projecting flanges —8— in substantially 105 the same flat plane, the opposite upright sides of each stud and its upright flanges —8— constituting guides for receiv-

ing the adjacent ends of the panels —3— and holding the latter against inward or outward displacement as will be hereinafter more fully described.

5 The braces —2—, which also perform the function of guy-rods, are preferably made mainly of wood and are provided at their lower and upper ends with metal inserts —9— and —10— firmly secured thereto, the 10 insert —9— being provided with a foot —11— adapted to rest upon the ground or other suitable support, said foot being provided with an aperture —12— for receiving a stake or holding pin —13—, which is driven into the ground to firmly hold that 15 end of the brace —2— in its adjusted position. The upper insert —10— is provided with a T-shaped head —14— adapted to enter a key-hole-slot —15— in the center of the stud —1— for interlocking engagement therewith, and thereby to hold the stud in 20 an upright position with its lower end resting upon the footing course —A—.

The T-shaped head —14— is somewhat 25 wider but of slightly less thickness than the width of the slot —15—, which is of slightly greater length than the width of the head —14— so that in attaching the brace —2— to the stud, it is necessary to turn said brace 30 to approximately a horizontal position to permit the entrance of the head —14— through the slot —15— whereupon the brace is returned to incline downwardly and its lower end is fastened by the stake to the 35 ground or another available support or if it is to be secured to a superposed staging, the foot —11— may be provided with additional apertures —12'— for receiving screws adapted to enter said staging.

40 Only one of these braces —2— is shown but it is to be understood that each upright stud —1— will be supported by a similar brace at both the inside and outside of the wall.

45 The panels —3— are preferably of uniform size convenient for handling except at the corners where they are usually bent to conform to the angles at the corners, both at the inside and outside of the walls as 50 shown in Fig. 1, but the opposite upright edges of each panel are provided with out-turned returned flanges —16— of slightly less width than half the width of the channel —7— of the stud —1— so that the adjacent flanges —16— may slide freely in 55 said panel as the panels are raised and lowered, thereby holding the panels in operative engagement with the studs against displacement in one direction, the portions of the 60 panels adjacent each stud being provided with additional out-turned lugs —17— constituting locking members for interlocking engagement of the outer faces of the flanges —8—, while the main bodies of the panels 65 engage the inner faces of said flanges, there-

by holding the panels against inward or outward displacement and also holding the studs in an upright position against inward, outward or lateral movement relatively to the panels.

70 In other words, the flanges —16— and lugs —17— constitute what may be termed 75 sliding interlocking connection with the studs —1— and permits the panels to be successively installed in operative position by the studs from the bottom upward with the lower edges of the superimposed panels resting upon the upper edges of the underlying panels, while the lower edges of the bottom panels rest upon the footing course —A—.

80 The cross-braces —4— are also preferably made of wood cut to a length corresponding to the thickness of the wall and placed across the intervening space between opposite studs so as to abut against the inner faces of the 85 corresponding panels in which position they are held by tightening the tie-wires —5—.

86 These tie-wires —5— are also extended across the intervening space between the inner and outer panels preferably close to the braces —4— and have their ends suitably anchored to the opposite upright studs —1— preferably by forming loops —18— on the ends of the tie-rods and passing said loops through apertures in the longitudinal centers of the studs where they are fastened by keys or pins —19—, thus permitting the inner portion of the tie-rods to be twisted by any suitable implement until the inner 90 faces of the panels are drawn tightly against the ends of the braces —4—, which latter prevent inner collapsing of the studs and panels and hold them in parallel upright relation while the tightened tie-rods —5— 95 serve to hold the studs and panels against 100 outward displacement.

105 The partitions —6— may be of any desired height and may be placed in any position required to form the upright sides 110 of any door or window reveal or other opening, but preferably extends entirely across the intervening space of the panels and are provided along their opposite upright edges with lugs —20— projecting through apertures or slots —21— in the panels —3—, said 115 lugs being provided with transverse apertures for receiving wedges or keys —22— by which the partitions are securely fastened to the opposite panels, (see Figs. 5 and 6).

120 As the work progresses, it becomes necessary to provide suitable staging or scaffold- 125 ing at the outside as well as the inside of the wall and consisting, in this instance of horizontal bars —23—, mainly of wood, upright wooden studs —24— and wooden plank 125 or platform —25—.

130 The horizontal bars —23— are provided at one end with metal inserts —26— having hook-shaped end lugs —27— adapted to enter vertically elongated slots —28— in the

longitudinal centers of the metal studs —1— as shown in Figs. 2 and 3 for detachably interlocking engagement therewith, the outer ends of said bars —23— being provided with metal side straps —29— bolted through the upright studs —24—.

The lower and upper edges of the several panels —3— are provided with out-turned flanges —31— for reinforcing purposes and 10 also to afford handles by which they may be placed in operative position and removed when necessary.

In assembling the form sections, a brace —2— may be attached to one of the upright studs —1— in the manner described and the stud with the brace thereon may then be placed in operative position upon the 15 footing course —A— and properly plumbed by shifting the foot of the brace along the ground or upon any suitable support after 20 which the stake —13— is driven into the ground to hold the brace and stud —1— attached thereto in its upright position, it being understood that the lower end of the 25 stud is substantially flat and wide transversely to assist in holding it in a vertical position against movement lengthwise of the wall.

The adjacent panels are then interlocked 30 with the opposite flanges —8— of the stud by downward sliding engagement therewith until the lower edges of the lowermost panels rest upon the footing course and thereby assist in firmly holding the stud against tilting 35 movement in either direction lengthwise of the wall.

The partition —6— if used, may then be 40 operatively connected to the panels at one side of the stud. The panels at the opposite side of the wall, which are to be attached to the partition, may then be placed 45 one upon the other and secured thereto by the adjacent keys —22— in which case, the studs at the corresponding sides of the wall which are to interlock with those panels may be slid downwardly from the top into 50 interlocking engagement with the edges thereof but where the partition —6— is not

used, the studs may be erected first one by one or successively from end to end of the wall 50 and the panels slip downwardly from the top into interlocking engagement with the flanges —8—, this operation being the same for both the outside and inside tiers of the forms. 55

It will be remembered that the braces —2— serve to hold the stud —1— against inward as well as outward displacement and enable both the inner and outer tiers of the panels to be erected in parallel relation, 60 the cross-braces —4— and tie-wires —5— being employed to further stiffen the forms during progressive erection of the concrete wall, the members —4— being removed as 65 the work progresses.

What I claim is:

1. In a concrete wall form, a channel iron stud adapted to be supported in an upright position and provided with opposite laterally projecting lengthwise flanges, and a panel 70 extending across the inner face of one of the flanges and provided with an outward projecting flange engaging the inner face of the adjacent side wall of the channel, said panel having a portion thereof engaging the outer 75 face of the flange of the stud to hold the panel against inward displacement from said stud.

2. In a concrete wall form, the combination of a channel iron having opposite 80 lengthwise flanges and constituting a stud, means for holding the stud in an upright position, panels slidable lengthwise of and upon said flanges and engaging the inner and outer faces thereof to hold the panels and 85 studs against relative inward or outward displacement, said panels having portions thereof projecting into the channel of the stud to hold the panels against lateral displacement from the stud. 90

In witness whereof I have hereunto set my hand this 22 day of October, 1921.

MARK S. HOTCHKISS.
